UNITED STATES PATENT OFFICE.

GEORGE R. SCHOENTHALER, OF CHICAGO, ILLINOIS.

SUPPORT AND TIE FOR CONCRETE-REINFORCING BARS.

1,254,853.

Specification of Letters Patent. Patented Jan. 29, 1918.

Application filed June 28, 1915. Serial No. 36,666.

To all whom it may concern:

Be it known that I, GEORGE R. SCHOENTHALER, a citizen of the United States, residing at Chicago, Illinois, have invented a certain new and useful Improvement in Supports and Ties for Concrete-Reinforcing Bars, of which the following is a full, clear, and exact description, such as will enable others skilled in the art to which it appertains to make and use the same, reference being had to the accompanying drawings, forming part of this specification.

My invention relates generally to reinforced concrete construction and more particularly to a combined chair and clip which is adapted to serve as a support and a tie for the metal bars used in reinforced concrete structures, such as floors, roofs, ceilings, walls and the like, and my present invention is an improvement on the form of chair and clip shown and described in my copending application filed November 18, 1914, Serial No. 872,752.

It will be understood that where metal bars or rods are utilized for reinforcing concrete construction, it is essential that said bars be tied together and supported a suitable distance above or away from the surface of the form or mold in order that when the concrete is poured said reinforcing rods or bars will be embedded in the concrete the required depth to properly reinforce it.

The principal object of my invention is to provide a comparatively simple, cheap and efficient chair or support and tie which can be readily combined with a single reinforcing bar or with two bars which are crossed and arranged substantially at right angles to each other, and which combined support and tie when properly applied for use ties the crossed bars to each other in a firm and substantial manner and maintains them in proper position while the concrete is being poured over and around said bars.

Further objects of my invention are to combine with a practically rigid support or chair, a tie, preferably in the form of a ductile wire, and which latter is permanently secured to the support at the time the device is manufactured.

In my present device, the tie wire being ductile to a considerable degree, can easily and quickly be bent upward from the support or chair into engagement with the supported bars and the ends of said wire can

be readily twisted together so as to firmly tie the bars together at the crossing points and at the same time firmly securing said support to said bars.

With the foregoing and other objects in view, my invention consists in certain novel features of construction and arrangement of parts hereinafter more fully described, claimed and illustrated in the accompanying drawings, in which—

Fig. 1 is a plan view of the blank section of sheet metal from which my improved chair or support is formed and showing the tie wire attached thereto.

Fig. 2 is a perspective view of a combined chair and clip of my improved construction, the same being applied to a pair of crossed reinforcing bars.

Fig. 3 is an end elevational view of a combined support and clip.

Fig. 4 is a side elevational view of the combined support and clip.

Fig. 5 is a side elevational view of a modified form of the support and clip.

Fig. 6 is a plan view of the blank section of sheet metal from which the modified form of the device is constructed.

Fig. 7 is a plan view of a further modified form of the device;

Fig. 8 is a side elevational view of the form illustrated in Fig. 7;

Fig. 9 is a perspective view of a further modified form of my improved support and clip.

Fig. 10 is a plan view of the blank section of sheet metal which is utilized in the construction of the form of clip illustrated in Fig. 9.

In the form of device illustrated in Figs. 1 to 4 inclusive the support or chair is constructed of a substantially rectangular, oblong, section of sheet metal, the same being bent at a centrally arranged transversely disposed line to form an inverted V-shaped body, the same comprising inclined legs 10, the lower ends of which are adapted to rest upon the false work or form which serves as a temporary support for the reinforced concrete construction. The lower ends of these inclined legs 10 are provided with upwardly projecting notches 11 which permit the semi-plastic concrete to flow freely into the space beneath the inverted V-shaped body.

The inclined legs 10 are each formed with one or more reinforcing or stiffening ribs

12, the same being pressed from the metal forming said legs, and such construction permits the chair or support to be constructed of comparatively light material, thus, to 5 a certain extent, decreasing the cost of production.

It will be understood that where the supports are constructed of comparatively heavy material, it will not be necessary to 10 reinforce or stiffen the legs.

Formed across the line of bend in the section of sheet metal which constitutes the body of the support, and preferably near the sides thereof are longitudinally disposed 15 slits 13 and the metal adjacent these slits is bent out of the normal plane to form loops 15, and the metal 16 between said loops and to the sides thereof is slightly depressed with respect to said loops.

20 The plan of manufacture of my improved device contemplates the feeding of a strip or ribbon of metal through automatically operated dies which cut the metal to proper shape, press the reinforcing ribs therein, 25 and provide the necessary slits 13 and loops 15, and after said loops have been formed and the metal adjacent thereto has been pressed as described a section of ductile wire 17 is threaded beneath loops 16 and over the 30 depressed portions of metal 16 between said loops. This operation takes place when the body of the support is still in flat shape, and the final operation in the formation of the device bends the legs 10 downward with respect to the section of wire, thus giving the chair or support its final shape. This bending of the leg portions to angular relationship crowds the portions of metal 16 upward into close engagement with the central portion 40 of the section of wire, and likewise draws the loops 15 downward on top of the wire, thereby firmly gripping the latter and permanently securing it to the inverted V-shaped base.

45 The end portions of the section of wire project horizontally from the sides of the support and in such condition the combined supports and clips can be readily nested for storage or shipment.

50 When this form of device is applied for use, the inverted V-shaped support is positioned beneath a pair of reinforcing bars at the crossing point with the lower portion of the lower bar resting in the seat or depression formed between the loops 15, and the end portions of the wire are now bent upward over the crossed bars and the ends of said wire are twisted together, thereby 55 securely tying said bars to each other and maintaining the same at the desired elevation above the form or false work on which the concrete is poured.

60 In the form of device illustrated in Figs. 5 and 6, the metal to the sides of the longitudinally disposed slits 13^a is depressed to

form downwardly projecting loops 16^a and that portion of the metal between the slits 13^a is bent upward to form a centrally disposed loop 16^b. The wire in this instance is inserted beneath loop 16^b and above loops 70 16^a while the body of the support is in flat condition; and when said support is bent to final shape, the wire is firmly gripped between the loops 16^a and 16^b.

In the modification illustrated in Figs. 7 75 and 8, the support or chair is preferably of inverted U-shape and comprises a practically flat seat or table portion 18 from the ends of which depend legs 18^a. The seat portion is preferably reinforced or stiffened 80 by one or more ribs 19, pressed in the metal of which the support is formed, and said ribs preferably extend downward a distance in the legs 18^a.

In this form of the device, the tie wire is 85 inserted beneath the central portion of the seat portion 18, and is clasped in depending loops 20 which are formed at opposite corners of the seat portion. After the insertion of the wire, the next operation in the manufacture of the device stamps the corrugation or rib 19, and bends downwardly at the same time the leg portions 18^a, and this operation tends to draw the metal in the seat portion 90 so as to firmly clamp or grip the wire between the metal forming the loops 20 and the metal of the adjacent parts of the seat portion.

In the modification illustrated in Figs. 9 95 and 10, the body of the chair or support is 100 substantially of channel-shape in cross section and comprises a vertically disposed web 21, horizontally disposed base flange 22, horizontally disposed top flange 23, and triangular legs 24, which latter are formed integral with the sides of web 21 and the lower ends of said legs terminating in the same plane with the underside of flange 22.

105 In this form of device, the tie wire is positioned in loops 25 which are cut from the metal of which the support is formed, said loops extending across the line of bend or the corner between web 21 and top flange 23.

A device of my improved construction is 110 comparatively simple, can be easily and cheaply manufactured, and by constructing the tie member of wire, said member can be 115 readily applied to the supported bar or bars and as the ends of the tie wire can be twisted together, the device is very efficient in connecting or tying together a pair of crossed reinforcing bars.

120 I am aware of various forms of devices which involve the combination of a base or supporting member and a separately formed 125 tie member, but such devices are not practical owing to the fact that separate parts can be readily lost or misplaced and the assembling of such parts involves the expenditure of considerable time and labor.

In so far as I am aware, I am the first to produce a combined support and tie for concrete reinforcing bars which involves a sheet metal base or support and a ductile tie wire 5 permanently secured thereto, and practically forming an integral part thereof.

A device of this character can be economically produced, can be readily applied to reinforcing bars and by virtue of the ductility 10 of the tying member, the same can be brought into close engagement with the supported bars, thereby tying the same together in an effective manner.

It will be readily understood that minor 15 changes in the size, form, and construction of the various parts of my improved device can be made and substituted for those herein shown and described, without departing from the spirit of my invention, the scope 20 of which is set forth in the appended claims.

I claim:

1. A reinforcement supporting device comprising a supporting member in the form of a ductile sheet metal blank shaped 25 and bent to provide angularly disposed members and a loop across the line of bend therebetween, and a ductile tie member retained by said loop and secured therein by the metal drawn on the line of bend in the 30 shaping of the supporting member.

2. A device of the class described comprising a supporting member consisting of a ductile sheet metal blank cut and bent to provide angularly disposed members and a 35 loop adjacent the line of bend therebetween, and a ductile tie member retained in said loop and secured therein by metal drawn at the line of bend in the shaping of the supporting member.

40 3. An article of the class described comprising a supporting member consisting of a blank of ductile sheet metal cut and bent to provide angularly disposed members and a

loop adjacent the line of bend therebetween, and a ductile tie member retained in said 45 loop and secured therein by metal displaced on the line of bend in the shaping of the supporting member.

4. An article of the class described comprising a supporting member consisting of 50 a blank of ductile sheet metal having a portion thereof slotted and shaped to form a loop, a ductile tie member disposed in said loop, and the supporting member being bent to form angularly disposed portions and 55 distorted portions at the line of bend therebetween, which latter engage the tie member to bind it in the loop.

5. A device of the class described comprising a ductile sheet metal supporting 60 member slotted to form a loop, a ductile tie member disposed in said loop, portions of the supporting member being bent relative to each other to provide angularly disposed portions, and a portion of the metal intermediate 65 said portions being distorted to bind the tie member in the loop.

6. An article of the class described comprising a supporting member of ductile sheet metal having deflected portions bent into an 70 angular relationship, a portion of said member being slotted to form a loop extending across the line of bend and having its ends integral with the deflected portions respectively, and a ductile tie member disposed in said 75 loop and retained on the supporting member by clamping coöperation of the loop and adjacent portion of the supporting member.

In testimony whereof I hereunto affix my signature, in the presence of two witnesses, 80 this 24th day of June, 1915.

GEORGE R. SCHOENTHALER.
